US00D529475S

(12) **United States Design Patent** (10) **Patent No.:** **US D529,475 S**
Lee et al. (45) **Date of Patent:** **** Oct. 3, 2006**

(54) **PORTABLE PHONE**

(75) Inventors: **Min-Hyouk Lee**, Sunwon-si (KR);
Chang-Hwan Hwang, Goyang-si (KR)

(73) Assignee: **Samsung Electronics Co., Ltd.**,
Suwon-si (KR)

(**) Term: **14 Years**

(21) Appl. No.: **29/241,324**

(22) Filed: **Oct. 27, 2005**

(30) **Foreign Application Priority Data**

Apr. 28, 2005 (KR) 30-2005-0014450

(51) **LOC (8) Cl.** **14-03**

(52) **U.S. Cl.** **D14/138**

(58) **Field of Classification Search** D14/137,
D14/138, 147-148, 247-248, 144, 496, 156,
D14/341-347; 379/433.01-433.13; 455/575.4,
455/566, 575.1, 556.1, 556.2, 90.3; D21/329,
